[57] ABSTRACT

An electrical shutter-control system to be used in a camera. The system includes a solenoid which responds to a signal for initiating shutter-closing operations. A signal-transmitting circuit transmits the signal to the solenoid and receives one of a plurality of timing signals from a timing circuit which is automatically operated to select a timing signal which will provide the best exposure. A signal-altering circuit detects when the conditions require a change in the selected timing signal for improving the exposure, and this signal-altering circuit measures the extent to which the selected timing signal should be changed and alters the timing signal accordingly so that the altered timing signal is transmitted to the solenoid for improving the exposure. The alteration in the timing signal is determined in accordance with a fractional interval of time between the time increments corresponding to the timing signals, so as to achieve a continuous exposure time adjustment, or according to non-linear film characteristics to compensate for the latter characteristics, or in accordance with both of these factors.

ELECTRICAL SHUTTER-CONTROL SYSTEMS FOR CAMERAS

BACKGROUND OF THE INVENTION

The present invention relates to cameras.

In particular, the present invention relates to shutter-control circuits for cameras.

There are known exposure-time controlling circuits of the digital type, in that these known circuits select a given timing resistor. With such known shutter controls an external exposure adjusting value is determined by the time constant which, in turn, is determined by a timing resistor selected in accordance with light received from the object to be photographed. The circuit includes a timing capacitor which has a constant capacity and which is connected in series with the timing resistors. The resistances of these timing resistors are pre-selected in such a way that they vary according to a multiple proportion, corresponding to the intensity of the light received from the object which is to be photographed, so that these timing resistors together with the timing capacitor develop exposure-time adjusting values which vary in accordance with a multiple proportion. As a consequence, with this type of shutter-control circuit it is only possible to achieve a discontinuous or stepping type of adjustment of exposure time. One of the important features of a timing resistor selecting type of electric shutter control circuit resides in the fact that it is well-suited for cameras which utilize internal light-receiving systems. However, such electrical shutter control circuits do not permit a continuous adjustment of the exposure time to be achieved so that they are limited to the extent that it is only possible to provide from such circuits certain preselected exposure times which vary from one to the next by given time intervals.

A further problem encountered with cameras resides in the characteristics of the film exposed therein. Thus, it is well known that film has a characteristic curve which does not vary linearly throughout the entire range of light intensity in which exposures are made. For example it is well known that at a lower range of light intensity the film characteristic is non-linear so that due to the nature of the film itself there are inherent inaccuracies when making exposures with a relatively small amount of light.

Thus, with conventional electrical shutter control systems the exposure time which is determined is always with respect to a limited range of light which represents only part of the entire range over which the film is exposed. There is a degree of disagreement between the exposure time which is automatically determined and the actual optimum exposure time for the film both at higher and lower ranges of light intensity. Thus, it is commonly known that the film characteristic is determined by the light-sensitive material used for the film, and it is impossible to achieve linearity in the film characteristic curve at both higher and lower ranges of light intensity where the film is likely to be over-exposed or under-exposed, even if the film has a constant γ -value. Thus, the proportional relationship between the light intensity and the density of the image which is formed in the film is lost at certain ranges of light intensity. In addition the proportional relationship may vary depending upon the developing solution which is used for the film as well as the developing time.

SUMMARY OF THE INVENTION

It is accordingly a primary object of the present invention to provide an electrical shutter-control system which is capable of operating circuits of the above type in such a way that the selected signals are altered to give the same effect as a continuous adjustment of exposure time.

Furthermore, it is an object of the present invention to provide for an electrical circuit of the above type a compensation which will automatically compensate for the non-linear characteristics of the film at certain ranges of light intensity.

It is furthermore an object of the present invention to provide circuitry of the above type which is relatively simple and inexpensive and which operates very reliably.

In accordance with the invention the electrical shutter control system includes an electrical means for responding to a signal for initiating shutter-closing operations. A signal-transmitting means is electrically connected with the electrical means for transmitting a signal thereto. A timing circuit means is electrically connected with the signal-transmitting means for delivering to the latter, to form at least part of the signal transmitted thereby to the electrical means, one of a plurality of timing signals which differ from each other by increments corresponding to different time intervals. An electrical selecting means is electrically connected with the timing circuit means for selecting from the latter, to be delivered to the signal-transmitting means, that one of the plurality of timing signals which will provide the best exposure. An electrical operating means is electrically connected with the selecting means for operating the latter to select this particular timing signal which will provide the best exposure. An electrical signal-altering means is provided for automatically detecting when the photographing conditions require a change in the selected timing signal so as to improve the exposure as well as for determining the extent to which this selected time signal should be changed in order to improve the exposure. This signal-altering means is electrically connected with the signal-transmitting means for altering the selected timing signal received thereby to the extent determined by the signal-altering means before a signal is transmitted to the electrical means which initiates the shutter-closing operations. In this way this latter electrical means will receive a timing signal which, if necessary, is altered to improve the exposure.

BRIEF DESCRIPTION OF DRAWINGS

The invention is illustrated by way of example in the accompanying drawings which form part of this application and in which:

FIG. 1 illustrates an electrical circuit forming one embodiment of the invention;

FIG. 2 is a graph illustrating the configuration of an altering signal generated with the circuitry of FIG. 1;

FIGS. 3a-3c respectively illustrate variations of that part of the circuitry of FIG. 1 which generates the signal illustrated in FIG. 2;

FIGS. 4a and 4b respectively show fragmentary circuits which explain the operation of embodiments such as those shown in FIGS. 3b and 3c;

FIG. 5 is a wiring diagram of a further embodiment of the invention;

FIG. 6 is a graph illustrating an altering signal generated with the circuitry of FIG. 5;

FIG. 7a is a wiring diagram of a further embodiment of circuitry according to the invention;

FIGS. 7b and 7c respectively illustrate graphically signals generated with the circuitry of FIG. 7a;

FIG. 8 is a fragmentary illustration of a different embodiment of an oscillating circuit capable of being used in place of the oscillating circuit of FIG. 7a;

FIG. 9 is a wiring diagram of a further embodiment of a shutter-controlling circuit of the invention;

FIG. 10 shows a variation of that part of the circuitry of FIG. 9 which compensates for film characteristics;

DESCRIPTION OF PREFERRED EMBODIMENTS

If an electrical shutter-control device operates in such a way that it obtains an exposure value as determined by

$$E = I \cdot t$$

(1)

where,

E = exposure value,

I = energy of the light, and

t = exposure time given by the shutter device, then the appropriate exposure will not be obtained in the lower light intensity region, because the film characteristic curve itself is not proportional to the light intensity in such a region. Thus, no matter how the electrical shutter-control circuitry may operate to determine exposure time in accordance with equation (1), there will be an unsatisfactorily exposed film both in the higher and in the lower light intensity regions.

In accordance with the present invention, the exposure value in the lower light intensity region is expressed as

$$E = I \cdot \beta \cdot t$$

(2)

where,

β = efficiency of the light sensitivity,

$$0 < \beta < 1,$$

and the light sensitivity efficiency of the light energy is compensated with the exposure time given by the shutter-control circuit so as to avoid this disadvantage.

Thus, when the exposure time determined by the shutter-control system is t at an intermediate light intensity region and t/β in the lower light intensity region, then the exposure time will meet the film characteristics. In order to satisfy this requirement the exposure time given by the shutter-control system should be increased to some extent in the lower light intensity region.

As is well known, a timing resistor selecting type of electrical shutter-control circuit adjusts the exposure time in a stepwise manner. With the present invention it is possible to provide an improved circuitry to be accommodated to such an electrical shutter-control device for adjusting the exposure time continuously. In addition, with the circuitry of the invention there is provided an automatic means which will compensate for the exposure time in such a way as to enable the exposure time to be adjusted with the electrical shutter-control system of the invention so as to meet the particular characteristics of the film in the camera.

For this purpose it is proposed with the present invention to make use of a timing resistor selecting type of electrical shutter-control circuit provided with a timing circuit which is made up of a plurality of timing resistors to be selectively inserted into the circuit depending upon the intensity of the light received from the object to be photographed, this circuit including a timing capacitor which is connected in series to the timing resistors and a switching circuit which receives the adjusted information from the timing circuit so as to determine the adjusting values in a stepwise manner. Thus, the switching circuit and the capacitor form a signal-transmitting means for transmitting a signal to an electrical means which will initiate shutter-closing operations. A signal-altering means of the invention develops a control voltage to achieve altering signals the levels of which are determined within the minimum range of the adjusting value with the variation of the altering signal depending upon the intensity of the light received from the object to be photographed, and the operation of the signal-transmitting means is controlled by these altering signals so that a continuous adjustment of the exposure time is made possible even when using such a timing resistor selecting type of electrical shutter-control system.

It is furthermore proposed with the invention to provide a signal-altering means where when exposures are made at relatively low light intensity, corrections are automatically carried out in such a way that the altering signal has an increasingly larger amplitude toward the lower light intensity region in the event that photographs are made with a relatively small amount of light. Also, in the case where the altering signal is maintained at a constant amplitude it is possible to change the voltage level at which the altering signals are generated so as to compensate for the film characteristics. In this way it is possible to achieve a continuous adjustment of exposure time with a timing resistor selecting type of electrical shutter-control system while at the same time it is also possible to adjust the exposure time in order to compensate for exposures made at a region of low light intensity.

In the embodiment of the invention which is illustrated in FIG. 1, the electrical shutter-control system is constructed in such a way as to determine a timing signal in a stepwise manner by operation of a switching circuit which receives adjusting information from a

timing circuit made up of a plurality of timing resistors which are selectively inserted in the circuit depending upon the intensity of the light received from the object to be photographed. These resistors are electrically connected on the one hand with a timing capacitor and on the other hand with a transistor, the latter components forming a signal-transmitting means. The electrical shutter-control system of FIG. 1 includes a signal-altering circuit itself made up of a composite resistor means which includes a plurality of separate resistor elements as well as a light-responsive component connected in series with the composite resistor means. Each of the several separate resistor elements respectively form pairs with each of the timing resistors and are supplied with current when an associated timing resistor has been selected. The variation range of the terminal voltage across the composite resistor means of the signal-altering circuit is determined by the common ratio of the multiple proportion preselected in association with the resistor elements which are sequentially supplied with current simultaneously with the selection of the associated timing resistors, and the trigger voltage of the switching circuit which forms the signal-transmitting means is controlled according to the voltage level determined by the intensity of the light received from the object to be photographed, so that a continuous adjustment of the exposure time is made possible with a timing resistor selecting type of electrical shutter-control system.

Thus, referring to FIG. 1, there is illustrated therein a wiring diagram of a timing resistor selecting type of electrical shutter-control system which includes a signal-altering means of the invention. There are illustrated in FIG. 1 elements 1-4 which respectively form components of a circuit for selecting a given exposure time from among a plurality of different exposure times which differ from each other by increments corresponding to different time intervals. Thus, the circuit includes the photosensitive means 1 which responds to the light received from the object to be photographed in a well known manner. This light-responsive component 1 is connected in series with a bleeder resistor 2, and a selecting means 3 is electrically connected to a junction between the components 1 and 2. This electrical selecting means 3 is thus operated by the light-responsive means 1, 2 and serves to select from a timing circuit 4 a timing resistor circuit which will correspond to a given light intensity. Thus, the timing circuit means 4 includes a plurality of timing resistors 4a, 4b, and 4c adapted to condition the light from the object to be photographed in accordance with a multiple proportion. These resistors are connected in parallel with each other. The several resistors 4a, 4b, and 4c, are respectively connected in series with switching transistors 4a', 4b', and 4c'. The bases of the latter transistors are all connected to the electrical selecting means 3, so that each of the transistors becomes conductive in response to a timing resistor selecting signal received from the selecting means 3. The selected timing signal is transmitted to a signal-transmitting means which includes a timing capacitor 5 connected in series with the timing circuit means 4, so as to form therewith a structure for participating in the transmission of a suitable timing signal to the electrical means 7 in the form of a solenoid for responding to the transmitted signal in order to initiate the shutter-closing operations in a well known manner. The signal-transmitting means includes

in addition to the capacitor 5 a switching transistor 6 electrically connected directly with the electromagnet 7.

The signal-altering means of the invention is electrically connected in the embodiment of FIG. 1 with the transistor 6 and includes a transistor 8 which operates to control the trigger level of the switching transistor 6. The emitter terminals of the transistor 6 and 8 are both coupled with a trigger resistor 9. The circuitry includes 10 a shutter-releasing switch 10 constructed so as to operate in synchronism with depression of a shutter button. The switch 10 is normally closed so as to bypass the timing capacitor 5.

The signal-altering means of the embodiment of FIG. 1 includes the signal-altering circuit 11 which develops the signal-altering signal to be applied by way of the transistor 8 to the transistor 6 so as to alter the signal transmitted to the electrical means 7. The signal-altering means 11 includes the resistor-transistor composite 12 connected in series with a light-responsive means formed by the light-sensitive component 13. The resistor-transistor composite 12 consists of a plurality of resistors 12a, 12b, and 12c connected in parallel with each other. These resistors are respectively connected 20 in series with switching transistors 12a', 12b', and 12c'. The terminal voltage across the resistor-transistor composite 12 is applied to the base of a transistor 14 of the signal-altering means. A resistor 15 is connected in the emitter circuit of transistor 14, and the signal-altering means includes a memory capacitor 16 capable of being connected in parallel with the resistor 15 by way of a change-over switch 17. The bases of the several transistors 12a', 12b', and 12c' are respectively connected 25 to the selecting means 3 in the same way as the bases of the transistors 4a', 4b' and 4c', respectively, so that a signal selecting a given timing resistor will be simultaneously transmitted to the bases of a given pair of transistors 4a' and 12a', 4b' and 12b', or 4c' and 12c'.

FIG. 1 illustrates a power source switch 18 as well as a power source 19. The signal-altering means further includes the normally closed contact 17a and the normally open contact 17b of the switch 17, the common terminal of which is connected to the capacitor 16 as illustrated. The normally open terminal 17b of the switch 17 is electrically connected to the base of the signal-altering transistor 8.

The embodiment of FIG. 1 illustrates a timing resistor selecting type of shutter-control system in which the timing resistors are sequentially selected with only one timing resistor being selected at any given time so that in accordance with the light intensity one timing resistor is selected, then the latter becomes unenergized and the next timing resistor is selected, and so on, until a selection is made of a timing resistor which will correspond most closely to the lighting conditions. For example, when the timing resistor 4b is to be selected after the timing resistor 4a has been inserted into the delay circuit, the timing resistor 4a will be disconnected from the delay circuit upon insertion of the subsequent timing resistor 4b. The same is true of the connection of the timing resistor 4c after the timing resistor 4b has been selected. These timing resistors have resistances varying in accordance with a multiple proportion. Thus, if it is assumed that the time constant of the timing resistor 4a and the timing capacitor 5 is set to correspond to an exposure time of 1/50 sec., then the time constant of the timing resistor 4b and the capaci-

tor 5 is set to give an exposure time of 1/100 sec., and the time constant of the resistor 4c and capacitor 5 is set to give an exposure time of 1/200 sec. Thus, the resistances of the resistors 4a, 4b, and 4c are pre-selected so that they reduce in magnitude in a stepwise manner. In the illustrated embodiment the timing circuit 4 includes only three timing resistors, but in practice any number of timing resistors may be used so as to spread the adjustable range of exposure time.

Assuming now that the switch 18 is closed prior to releasing the shutter, a certain photoelectrically converted information corresponding to light from the object will be applied by a divided voltage developed by the light-sensitive element 1 and the bleeder resistor 2 to the selecting means 3, so that the selecting means 3 will develop a selecting signal which will select any one of the resistors 4a, 4b, 4c. Assuming that the timing resistor 4a is selected, then an exposure time of 1/50 sec. will be provided, in accordance with the above example. It is to be noted that this exposure time will be provided even if the lighting conditions are such as to require a somewhat shorter exposure time. For example if it is assumed that actual lighting conditions are such as to require more precisely an exposure time between the 1/50 sec. provided by resistor 4a and the 1/100 sec. provided by resistor 4b, then the circuitry will operate to select the resistor 4a in the event that the error is smaller by selection of this particular resistor. Thus, the circuitry operates so as to select an exposure time which will provide the best exposure within the limitations inherent in the stepwise selection of timing signals which respectively correspond to increments without the possibility of choosing the values between these increments.

This latter factor is one of the great drawbacks of conventional timing resistor types of exposure-time selecting circuits, and with the present invention this drawback is avoided.

Thus, simultaneously with selection of the timing resistor 4a, in the above example, the switching transistor 12a' in the signal-altering circuit will turn on so as to supply current to the timing resistor 12a as well as to the light-responsive means 13. As a consequence, the terminal voltage across the timing resistor 12a will be applied to the base of the transistor 14 so as to render the latter conductive for accumulating a charge in the capacitor 16, this charge corresponding to the resistance of the timing resistor 12a. At the instant when the change-over switch 17 is actuated to engage the normally open contact 17b, the charge accumulated at the capacitor 16 will be transmitted through the transistor 8 to the transistor 6 for altering the signal received thereby from the timing circuit means 4. Under these conditions, when the shutter-releasing switch 10 is opened by depression of the shutter-operating button of the camera, the exposure-time determination circuit will operate, with the delay circuit consisting of the timing resistor 4a and the capacitor 5 being set into operation simultaneously with the mechanical opening of the shutter. In this way the subsequent closing of the shutter is brought about under control of the selected time constant or timing signal as altered with the altering signal delivered through the transistor 8 to the transistor 6. In this way any error in the exposure time will be automatically corrected.

As is apparent from the above description, the trigger voltage should be controlled continuously to cover and

meet the entire range of light sensitivity with a level corresponding to the gap between the timing resistors 4a and 4b. This requires a signal-altering circuit which has a special construction. Thus, the timing resistors 4a, 4b, and 4c have resistance values varying in accordance with a multiple proportion, and the difference between the light values of the light conditioned by the timing resistor 4a and by the timing resistor 4b as well as the difference in the light values of the light conditioned by the timing resistor 4b and the timing resistor 4c will be constant and equal with each other. So long as the resistances of the timing resistors are determined in accordance with a multiple proportion irrespective of the number of timing resistors, such differences in light values will be constant and equal and will form a common ratio therebetween.

The photoelectrically converted information of the light from the object, or the light corresponding to the common ratio, will be constant. Therefore, by setting the resistances of the timing resistors 12a, 12b and 12c in such a manner that the divided voltage V_m derived from the photoelectrically converted information is developed at the junction point A of the signal-altering circuit 11, this divided voltage V_m will vary with the change in the internal resistance of the light-sensitive component 13, and the upper limit of the voltage V_m will be determined within the voltage range $V_m - V_0$ of the photoelectrically converted information.

Assuming that the timing resistor 12a is selected, then the voltage V_1 at the junction point A will be

$$V_1 = [(r_1)/(R_1 + r_1)]E$$

where, R_1 is the internal voltage of the light-responsive component 13 when the timing resistor 12a is selected, r_1 is the resistance of the timing resistor 12a, and E is the voltage of the power source 19.

This equation shows that the voltage V_1 at the junction A varies with the change in the internal resistance of the light-responsive means 13. This variation may be plotted to form a graph as shown in FIG. 2. As is apparent from the graph of FIG. 2, the voltage at the junction point A rises along a steep slope between the internal resistance r_1 up to the resistance r_2 of component 13 until the voltage V_m is reached. In this manner the voltage at the junction point A reaches V_m but never exceeds V_m , and when it does reach V_m , the timing resistor 12b (having a resistance of r_2) will be selected.

At the instant when the timing resistor 12b is selected, the voltage V_2 at the junction point A will be

$$V_2 = [(r_2)/(R_2 + r_2)]E$$

where, R_2 is the internal resistance of the light-sensitive component 13 when the timing resistor 12b is selected, and

r_2 is the resistance of the timing resistor 12b.

Thus, the voltage V_m at the junction point A will be lowered rapidly to V_0 due to the newly inserted resistances R_2 and r_2 .

In order to satisfy the above relation, the voltages V_m , V_1 and V_2 should be set depending upon the common ratio between the resistances of the timing resistors as $V_m = V_1 = V_2$.

Therefore, the relation between the resistors 12a and 12b will be expressed as

$$\frac{r_1}{R_1+r_1} = \frac{r_2}{R_2+r_2} \quad r_2 = \frac{R_2}{R_1} r_1$$

(3)

This means that the resistance r_2 of resistor 12b should be selected as $[R_2/R_1] r_1$.

In the same way, the resistance r_3 of timing resistor 12c should be

$$r_3 = (R_3/R_2) r_2$$

(4)

where, R_3 is the internal resistance of the light sensitive element 13 when the resistor 12c is selected.

The voltage V_m determined by the common ratio of the resistances of the timing resistors will in turn be determined by

$$R_1 = R_{o1} 2^{-(b+\alpha_1)\gamma}$$

Accordingly, if the intensity of light from the object conditioned by the timing resistors 4a and 4b are α_1 L.V. and α_2 L.V., respectively, the common ratio will be

$$\frac{R_{o1} 2^{-(b+\alpha_1)\gamma}}{R_{o1} 2^{-(b+\alpha_2)\gamma}} = \frac{R_{o1}}{R_{o1}} \cdot \frac{2^{-\alpha_1\gamma}}{2^{-\alpha_2\gamma}}$$

(5)

Thus, the common ratio will be constant as long as the time constants are set in accordance with a multiple proportion. From equations (3) and (4)

$$r_2 = \frac{2^{-\alpha_1\gamma}}{2^{-\alpha_2\gamma}} r_1$$

$$r_3 = \frac{2^{-\alpha_1\gamma}}{2^{-\alpha_2\gamma}} r_2$$

By selecting the timing resistors 12a, 12b, and 12c in this way, the continuous adjustment of the exposure time corresponding to the interval or gap between any two adjacent timing resistors will be made possible under continuous control of the trigger voltage.

As has been pointed out above, with the circuitry of FIG. 1 selection is sequentially made from one timing resistor to the next. These circuits also can be constructed so as to have the timing resistors accumulatively selected with the circuit operating in such a way that after the timing resistor 4a, for example, has been inserted in the delay circuit, the timing resistor 4b which is to be inserted subsequently in the delay circuit will form a parallel-connected composite resistor with the resistor 4a, and then both of these parallel-connected resistors are electrically connected to the capacitor 5.

FIGS. 3a, 3b, and 3c represent three different forms of signal-altering circuits 11 to be used with a timing resistor type of circuit where the timing resistors are accumulatively connected into the circuit. In FIGS. 3a-3c the various components are designated by the same reference characters as in FIG. 1.

In the embodiment illustrated in FIG. 3a, the resistors 12a, 12b, and 12c of the illustrated signal-altering

means are selected accumulatively and form a composite resistor so as to determine the voltage at junction point A. For example, if the timing resistors 4a and 4b are selected, the switching transistors 12a' and 12b' will be turned on to thereby combine the resistor elements 12a and 12b in parallel for connecting them to the light-sensitive element 13. Therefore, the resistances of the resistor elements is set in such a way that the voltage developed at junction point A by the composite resistor consisting of the newly added resistor element 12x and the resistor element 12a becomes equal to the voltage V_1 at the junction point A of the preceding embodiment. In the same way, the voltage developed at the junction point A by the composite resistor consisting of resistor elements 12x, 12a, and 12b is set equal to the voltage V_2 at junction point A of FIG. 1. By setting the resistance of each resistor element, it becomes possible to develop an inclined, sawtooth voltage curve as illustrated in FIG. 2.

In the embodiment illustrated in FIG. 3b, the signal-altering means is provided, not with resistors, but instead with diodes 20a, 20b, and 20x. In this case the number of diodes used cannot be determined according to a definite rule, but the voltage at junction point A will theoretically form a slope as illustrated in FIG. 2 if the number of diodes employed corresponds to the square of the L.V. and the diodes employed have an equal and constant characteristic with respect to each other.

This relationship is described mathematically below: Referring to FIG. 4a, part of the circuitry of FIG. 3b is illustrated. Utilizing symbols as shown in FIG. 4a, V_1 will be expressed as

$$V_1 = I_{n1} (E/R_1)$$

(6)

Since $i1$ is nearly equal to E/R_1 ,

$$V_1 \approx I_{n1} (E/R_1)$$

(in the above equation it is assumed that the possible voltage drop developed in the diode D_1 by means of $i1$ is negligible compared with V_1 , and that the proportional ratio is unity for convenience of explanation.)

Assuming that the resistances of timing resistors 4a, 4b, and 4c are preselected at an interval corresponding to 1 L.V., then the voltage V_1 will rise up in an inclined slope in accordance with the equation (6) until a level corresponding to the increase of 1 L.V. is reached in the light from the object, and at this instant the subsequent stage timing resistor will be selected. If the internal resistance of the light sensitive element 13 is expressed as R_2 , the current i_1 will become i_2

$$i_2 = E/R_2$$

As a result, the terminal voltage of diode D_1 will be changed from V_1 to

$$V_2 \approx I_{n2} (E/R_2)$$

Assuming that the internal resistance R_1 of the photo-sensitive element 13 corresponds to the rising point of the terminal voltage V_1 , the terminal voltage V_2 will be the voltage at the point where the intensity of light from the object has been increased by 1 L.V.

If the internal resistances R_1 and R_2 are assumed to be

$$R_1 = R_{o1} 2^{-\delta\gamma}$$

and

$$R_2 = R_{o1} 2^{-(\delta + 1)\gamma},$$

$$V_1 = I_n (E/R_{o1}) 2^\delta$$

(7)

$$V_2 \approx (E/R_{o1}) 2^{\delta\gamma} \cdot 2^\gamma$$

(8)

where,

R_{o1} = resistance of photosensitive element 13 when it receives no light,

E = power source voltage,

b = L.V. -equivalent value, and

γ = γ -value of photosensitive element 13. Therefore

$$V_2 > V_1$$

In order to develop the repeated inclined voltage providing the sawtooth curve as shown in FIG. 2, the condition $V_1 = V_2$ is required. When a diode D_2 which is equal to the diode D_1 is added as illustrated in FIG. 4b, the current i_2 will be divided into two currents, respectively flowing through the diodes D_1 , D_2 which have equal characteristics. Each half of the divided current will be expressed as $i_2/2$, so that the terminal voltage V'_2 will be

$$V'_2 = I_n (i_2/2) = I_n (E/2R_2) = I_n (E/2R_{o1}) 2^{\delta\gamma} \cdot 2^\gamma$$

In the above equation if $\gamma = 1$

$$V'_2 = I_n (E/R_{o1}) 2^\delta$$

(9)

Equation (9) is equal to equation (7), if γ is unity. Therefore, the voltage at junction point A drops to zero at any time when the light value increases by 1 L.V. The relationship according to which equations (7) and (9) are equal under such a condition that $\gamma = 1$ will apply equally at a given light value b and at a light value $b+1$ which is increased by 1 L.V. above b . Thus, the terminal voltage will ascend until the light value increases by 1 L.V., then will drop abruptly to zero. This variation will be repeated so that sawtooth voltage curve will be formed.

FIG. 3c illustrates an arrangement where each branch has a plurality of series-connected diodes coupled together for varying the resistances of the branches. According to this embodiment, since the resistance of each branch can be preset at an optional value, it is possible also with this embodiment to develop an inclined voltage at the junction point A in the same manner as illustrated in FIG. 3a.

It is to be noted, therefore, that the electrical shutter-control system of the invention while accommodating a timing circuit means 4 having timing resistors which are used accumulatively can also provide a continuous adjustment of the exposure time within any interval between any two adjacent timing resistors as a result of the signal-altering means 11 as illustrated in FIGS. 3a-3c.

Thus, according to the above embodiments a photosensitive element and a composite resistor means consisting of a plurality of resistors or diodes associated with each branch are connected in series so that the

terminal voltage of the composite resistor means always corresponds to the trigger control voltage for adjusting the exposure time within the interval between any two adjacent timing resistors. Therefore, even if the intensity of light from the object has a value within the interval between the light values corresponding to the timing resistors and a subsequent timing resistor, the trigger voltage can be controlled continuously in accordance with the added portion of light intensity

which is required and which cannot be covered by the first timing resistor. In this way an accurate and continuous adjustment of the exposure time may be made by using the time constant determined by the selected timing resistor and the capacitor of the signal-transmitting means, and then by altering the signal with the signal-altering means of the invention to achieve a controlled trigger voltage. In this way a timing resistor selecting type of electrical shutter-control system can be operated to provide a continuous adjustment of the exposure time.

In the above embodiments, electromagnetic relays or the like may be used instead of the switching transistors 4a', 4b', and 4c' in the timing circuit means 4 as well as instead of the switching transistors 12a', 12b', and 12c' in the signal-altering means 11. In addition, any desired number of timing resistors and resistor elements or diodes may be employed in the timing circuit means 4 and the signal-altering means 11.

FIG. 5 illustrates another embodiment of a shutter-control system of the invention. This embodiment is also capable of altering the timing signal so as to achieve a continuous exposure time control rather than a stepwise control. In addition, with the embodiment of FIG. 5 it is possible to alter the signal so as to compensate for the film characteristic in a range of low light intensity. The illustrated system is constructed so as to determine the exposure time in a stepwise manner by operation of the conventional timing circuit which has the plurality of timing resistors to be selectively inserted into the circuit depending upon the light intensity received from the object to be photographed, the inserted resistor or resistors being electrically connected with a signal-transmitting means which includes a timing capacitor connected in series to the timing resistors. The shutter-control system of the invention includes a signal-altering means which in the embodiment of FIG. 5 also is made up of a composite resistor assembly including a plurality of separate resistor elements and these elements are electrically connected with a photosensitive element connected in series with the composite resistor assembly. Each of the plurality of separate resistor elements forms a pair with a corresponding timing resistor and is supplied with current when the associated timing resistor has been selected by the selecting means. The variation range of the terminal voltage across the composite resistor means is determined according to a common ratio of the multiple proportion preselected in association with the resistor elements which are sequentially supplied with current simultaneously with the selection of the associated timing resistors. The voltage level determined in accordance with the light received from the object is raised in a lower light intensity region so that it corresponds with the characteristic curve of the film, and this latter rise in the voltage is provided by the signal-altering means of the invention which alters in a corresponding manner the signal transmitted to the solenoid which

50

55

60

65

forms the means which responds to initiate the shutter-closing operations, so that in this way with the embodiment of FIG. 5 the exposure time is increased when photographing under low light intensity conditions.

Referring now to FIG. 5, the electrical system illustrated therein is a timing resistor selecting type of electrical shutter-control system which accommodates an automatic means in order to compensate for the step-wise selection of exposure time. In the wiring diagram of FIG. 5 there are illustrated a photosensitive means 21 which senses the light from the object to be photographed, this photosensitive means 21 being connected in series with a bleeder resistor 22 so as to form therewith an electrical operating means which is electrically connected with the electrical selecting means 23 which selects a given timing signal from the timing circuit means 24 of FIG. 5. The timing circuit means 24 includes the plurality of timing resistors 24a, 24b, 24c, 24d, and 24e, connected in parallel with each other and adapted to condition the light from the object in accordance with a multiple proportion. The several timing resistors are respectively connected electrically with the switching transistors 24a', 24b', 24c', 24d', and 24e' which are electrically connected to the electrical selecting means 23 so that each of the switching transistors turns on in response to a selecting signal intermittently developed at the circuit of the selecting means 23. The signal-transmitting means to which a timing signal is delivered from the timing circuit means 24 includes the capacitor 25 and the transistor 26. Thus, the circuit means 24 is connected in series with the capacitor 25. The switching transistors 26 of the signal-transmitting means is arranged so as to become conductive in response to the time constant determined by the selected timing resistor and capacitor 25 so that in this way a signal will be transmitted to the solenoid 27 which is inserted in the collector circuit of the switching transistor 26 and which forms the electrical means for responding to the transmitted signal in order to initiate the shutter-closing operations. A shutter release switch 30 is operated in synchronism with depression of the shutter button. The switch 30 is normally closed and bypasses the capacitor 25.

The embodiment of FIG. 5 is provided with a signal-altering means 31 for developing a control voltage, the altering circuit 31 including a plurality of resistors 32a, 32b, 32c, 32d and 32e which are connected in parallel with each other. The several resistors 32a-32e are respectively connected in series with the switching transistors 32a', 32b', 32c', 32d', and 32e' in order to form a resistor-transistor combination, to which in turn there are connected in series the photosensitive element 33 and a transistor 34 to receive the terminal voltage of the resistor-transistor combination 32 at the base thereof. A resistor 35 is coupled to the emitter of transistor 34, and a memory capacitor 36 is connected in parallel with the resistor 35 when the switch 37 is in its normal position shown in FIG. 5 engaging the switch contact 37a. The bases of the several transistors 32a'-32e' are coupled with the selecting means 23 in the same way as the bases of the transistors 24a'-24e', respectively, so that the selection signals are transmitted simultaneously to a pair of base terminals of a pair of associated transistors 24a and 32a', 24b' and 32b', 24c' and 32c, 24d' and 32d', or 24e' and 32e', these selection signals being transmitted at equal and constant intervals.

FIG. 5 also illustrates the power source switch 38 and the power source 39. The switch 37 has a normally open contact 37b which can be closed when the switch 37 is changed over from contact 37a to contact 37b. 5 This contact 37b is electrically connected to the base of transistor 28 of the signal-altering means, so that through the latter the signal received by the transistor 26 from the timing circuit means 24 is altered as required before being transmitted to the electrical means 10 27.

The embodiment illustrated in FIG. 5 has a timing circuit means 24 in which the resistors are sequentially selected so that specific timing resistors are selected separately one from the other in order to provide the 15 exposure time selected by the selecting means 23. Thus, if the timing resistor 24b is to be selected after the timing resistor 24a has been inserted into the delay circuit, this timing resistor 24a will be disconnected from the delay circuit simultaneously with the connecting 20 of the resistor 24b into the circuit. The same is true in connection with any pair of successive timing resistors 24b and 24c, or 24d and 24e. The resistances of the timing resistors 24a, 24b, 24c, 24d, and 24e are pre-selected in accordance with a multiple proportion. 25 Therefore, if the time constant of the timing resistor 24a and the capacitor 25 is set to correspond to an exposure time of one-eighth sec., the time constant determined by the timing resistor 24b and capacitor 25 will give an exposure time of one-fifteenth sec., and the timing resistor 24c, 24d, and 24e will respectively provide 30 exposure times of one-thirtieth sec., one-sixtieth sec., and one one hundred twenty-fifth sec. In the illustrated embodiment the timing circuit means 24 includes for purposes of illustration only five timing resistors, but in 35 a practical device any number of timing resistors may be employed to provide a wider range of adjustment of the exposure time.

Thus, it will be understood that the embodiment of 40 FIG. 5 is similar to that of FIG. 1 and permits a continuous adjustment of exposure time to be achieved because of the altering of the signal from the timing circuit means 24 by way of the altering signal received through the transistor 28 from the signal altering means 45 31 which includes the transistor 28. Thus, the continuous control of exposure time is achieved with a saw-tooth shaped voltage curve as described above in connection with FIG. 2.

However, in the embodiment of FIG. 5 the resistors 50 32a and 32b, which are supplied with current in a lower light intensity region, have their resistance values set in such a way that they develop an inclined voltage as described above but with a change as illustrated in FIG. 6 and as described below.

In this way it will be possible for the signal-altering 55 means of FIG. 5 not only to achieve a continuous exposure time adjustment but also to compensate for the film characteristic which is non-linear in the low light intensity region.

Thus, with the embodiment of FIG. 5 the values of 60 the resistances of resistors 32a and 32b are set in accordance with the non-linear portion of the film characteristic curve (i.e. the lower light intensity region). Thus, when it is determined that the resistor elements 32a and 32b are to be supplied with current, the inclined voltages will have higher upper limit values, as indicated at a and b in FIG. 6. In other words, with the 65 embodiment of FIG. 5 the construction is such that the sig-

nal transmitted by the signal-transmitting means 25, 26 to the electrical means 27 is altered by the signal-altering means 31 so that the trigger voltage is increased in the non-linear portion where there is a lower intensity of light received from the object to be photographed, so that in this way it is possible to extend the exposure time when making an exposure with a relatively low light intensity.

Thus, with the above structure a timing resistor selecting type of electrical shutter-control system is provided in order to insure that the exposure time is consistent with the film characteristic even in a lower light intensity region so that unsatisfactorily exposed negatives will be avoided, so as to overcome this latter problem which has been considered inevitable when making photographs under conditions of low light intensity.

The automatic means for compensating the exposure time according to the present invention provides the same photographing conditions in the lower light intensity region as in the higher light intensity region. With the provision of such an automatic means, the electrical shutter-control system of the invention operates advantageously when making photographs in theatres or the like, where the available light is at a low range of intensity and where flash photography is prohibited. In addition, the automatic exposure time compensating circuitry of the invention can be incorporated into a continuous exposure time adjusting circuit arrangement having a timing resistor selecting type of electrical shutter-control device as pointed out above. This is advantageous in that automatic exposure time compensating means can be constructed relatively simply and can be accommodated in a camera housing which offers only a limited amount of space.

In the lower light intensity region the embodiment of FIG. 5 will provide the extended exposure time in accordance with the light intensity. However, when the embodiment of FIG. 5 is used to control exposure time in an inexpensive camera, this embodiment may be constructed in such a manner that it provides an extended exposure time in a lower light intensity region below the predetermined low light intensity value.

By selecting the resistances of the resistor elements which are to be supplied with current in the higher light intensity region in such a way that they follow the non-linearity of the film characteristic at the higher intensity region, it is possible also to construct the automatic means so that it will compensate the exposure time in the higher light intensity region in accordance with the teachings of the present invention.

FIGS. 7a and 8 respectively illustrate different embodiments of an electrical signal-altering means according to the invention. In each of these embodiments there is an oscillation circuit which forms the electrical operating means to operate the electrical selecting means which selects the timing signals from the timing circuit means. The oscillating circuits of these embodiments deliver operating pulses to the selecting means. The signal-altering means is electrically connected to the oscillating circuit in order to develop the sawtooth shaped curves varying within the range corresponding to the variation in the exposure time values, with each of these exposure time values being determined according to the selection of a timing resistor. The pulses which operate the selecting means are generated at the same frequency as the sawtooth signals. The signal-altering means of this embodiment has a memory ca-

pacitor which is charged and discharged each time a sawtooth signal changes. These embodiments include a time determining circuit in the form of a light-responsive circuit means electrically connected with the operating means for determining the duration of operation thereof. This light-responsive circuit means is also connected with the signal-altering means so as to actuate the latter to transmit to the signal-transmitting means any quantities stored at the memory capacitor of the signal-altering means when the operation of the operating means is terminated. The light-responsive circuit means which determines the duration of operation receives light from the object to be photographed and uses this information to provide equal and constant intervals corresponding to the period of the sawtooth signals and the pulse signals. Under the operation of this light-responsive circuit the memory means has its operation stopped so as to transfer the memorized electrical quantity to the signal-transmitting means to form the altering signal. Thus, with these operations the oscillation which provides the pulses is interrupted and the number of timing resistors to be selected is determined by the number of pulses which are developed, so that an exposure time adjusting value is obtained which corresponds to the pre-selected interval between the timing resistors of the timing circuit means. In this manner the trigger section of the switching circuit can be controlled depending upon the actual light intensity within the interval between the timing resistors, so that a continuous adjustment of exposure time is achieved in proportion to the intensity of light received from the object which is to be photographed.

Referring to FIG. 7a, the electrical selecting means 41 and the timing circuit means 42 are electrically connected to each other in a manner similar to the above-described embodiments. The timing circuit means 42 is made up of the plurality of timing resistors 42a, 42b, and 42c which are connected in parallel with each other. These resistors are respectively connected in series with the switching transistors 42a', 42b' and 42c' which respectively turn on when receiving at the bases thereof a selecting signal from the electrical selecting means 41 so as to thereby supply current to the selected timing resistor 42a, 42b, or 42c. The selected timing resistor will, by its series connection with the capacitor 43 of the signal-transmitting means, form a timing circuit.

The timing resistors 42a, 42b, and 42c are arranged in either of two different ways. In one arrangement they are sequentially selected one after the other, while in the second arrangement they are accumulatively selected so as to be connected in parallel into a single composite resistor. The switching transistor 44 forms with the capacitor 43 the signal-transmitting means of this embodiment and is arranged so that it receives at its base the terminal voltage across the capacitor 43. The collector terminal of the transistor 44 is electrically connected to the electrical means formed by the solenoid 45 for initiating the shutter-closing operations in response to the signal received from the signal-transmitting means. A normally closed shutter releasing switch 46 serves to bypass the capacitor 43, this switch 46 being opened upon depression of the shutter-releasing button of the camera.

The above-described structure of FIG. 7a operates in the manner described above in connection with the

above embodiments. This embodiment of FIG. 7a includes the electrical operating means 47 in the form of an oscillating circuit which is electrically connected to the selecting means 41 to operate the latter with operating pulses, and this embodiment also includes the light-responsive circuit means 48 for determining the duration of operation.

The oscillating circuit 47 includes a timing circuit made up of a variable resistor 49 and a capacitor 50 which are connected in series to a power source 51. This circuit includes a unijunction transistor 52 having its emitter electrically connected to a junction between the resistor 49 and capacitor 50.

The signal-altering means includes an amplifying transistor 53 having its base electrically connected to the junction between the variable resistor 49 and capacitor 50. In addition the signal-altering means includes the memory capacitor 54 connected electrically to the output terminal *b* of the amplifying transistor 53. The output terminal or first base *a* of UJT 52 is electrically connected to the electrical selecting means 41 for transmitting thereto the operating pulses developed at the terminal or junction *a*, and in response to these operating pulses the selecting means 41 will operate to select an appropriate timing resistor 42*a*, 42*b*, or 42*c* depending upon the received operating pulses. The memory capacitor 54 which is connected to the output terminal *b* of the amplifying transistor 53 is electrically connected to the common terminal 55*c* of a change-over switch 55 so that it normally is electrically connected to the terminal *b* through the normally closed switch contact 55*a*. The switch 55 includes a normally open contact 55*b* which is electrically connected to the base of transistor 56 of the signal-altering means so as to provide the altering signal to be combined with the signal from the timing circuit means 42 in order to provide the signal which is transmitted to the electrical means 45. Thus, the trigger level of the switching transistor 44 is controlled depending upon the electrical quantity stored in the memory capacitor 54. On the other hand, a trigger resistor 57 is electrically connected to the emitter terminals of the transistors 44 and 56 so that these transistors will cooperate electrically with each other.

It is to be noted that the oscillating frequency of the oscillating circuit 47 need not be set at a fixed value but may be set at any optional value as long as it maintains a constant relation with the light received from the object to be photographed. Thus, the logarithmically converted information of the light received from the object is to be conditioned at the same period as those of the oscillation pulses which continue to be generated at equal and constant intervals. As long as this condition is satisfied the oscillation frequency may be determined in such a way, for example, that the period of 1 sec. corresponds, for example, to 1 L.V.

The intensity of the light received from the object to be photographed can be conditioned at equal and constant intervals by converting it logarithmically. In order to further convert the logarithmically converted information into time-limiting information, the light-responsive circuit 48 is provided, this circuit 48 including a buffer transistor 60 connected at its base to a junction between the series-connected photosensitive element 58 and logarithmic conversion diode 59. A transistor 62 is connected through a variable resistor 61 to the emitter of the buffer transistor 60. A transistor

63 has its internal resistance adjusted under the control of the transistor 62. A timing capacitor 64 is electrically connected to the collector of the transistor 63. The transistor 63 forms a timing circuit together with the capacitor 64. A switching transistor 65 is arranged in such a way that it operates under the action of the timing circuit. In the collector circuit of the switching transistor 65 are inserted relay coils 66 and 67. The relay coil 67 is positioned so as to actuate the change-over switch 55 while the relay coil 66 serves to open the normally closed switch 66*a* which is connected to the terminal *a* of UJT 52 and to the selecting means 41. A power source switch 68 is provided so as to close during an initial increment of movement of the shutter-releasing plunger of the camera.

With the embodiment of FIG. 7a, when the power source switch 68 is closed prior to actual release of the shutter, the oscillating circuit 47 starts oscillating in accordance with the time constant of the variable resistor 49 and the capacitor 50. At this time UJT 52 oscillates at a preset constant frequency irrespective of the light received from the object to be photographed. As a consequence a series of operating pulses with a relatively small pulse width will appear at the terminal *a* of UJT 52 as a result of the characteristics thereof. Therefore, the selecting means 41 will be operated in response to these pulses so as to select timing resistors 42*a*, 42*b*, and 42*c* in the manner illustrated in FIG. 7b where the pulses are graphically shown.

Assuming now for purposes of explanation that the oscillating period of UJT 52 is set so as to be 1 sec., the signals appearing at the output terminal *b* will have the sawtooth configuration illustrated in FIG. 7c and having a period of 1 sec. The shape of the signal is determined by the emitter voltage of UJT 52.

On the other hand, inasmuch as the internal resistance of the light-responsive circuit 48 drops in response to the light received by the photosensitive element 58, the diode 59 will develop a logarithmically converted signal in accordance with the light from the object. Upon receipt of this signal all of the transistors 60, 62, and 63 will become conductive and will therefore supply current to the timing circuit formed by the transistor 63 and capacitor 64. As the internal resistance of transistor 63 varies in accordance with the logarithmically converted signal, which can be conditioned at an equal and constant interval, a transistor 65 which is rendered operative depending upon the time constant of the timing circuit will be turned on in accordance with the logarithmically converted signal. Therefore, by equalizing the value for conditioning the logarithmically converted signal at an equal and constant interval with the oscillation frequency of the oscillating circuit 47, the oscillating operation of the oscillating circuit 47 may be terminated in response to the light received from the object to be photographed. Assuming now that the transistor 65 is preset so as to turn on in 1 sec. at 1 L.V., in 2 sec. at 2 L.V., and so on, if the intensity of the light received from the object corresponds to 4 L.V., the transistor 65 will be rendered conductive in 4 sec. to thereby convert the light from the object into a time signal conditioned at an equal and constant interval. Accordingly, the opening of the switch 66*a* in the oscillating circuit 47 will be accompanied by the changeover of the switch 55 and thus the contact 55*a* will open while the contact 55*b* will close. In this case, assuming that the oscillating circuit 47 os-

cillates at a period of 1 sec., four operating pulses will be developed at the terminal *a* together with the development of four sawtooth signals at the output terminal *b*, so that four timing resistors will be sequentially selected. On the other hand, since the sawtooth signals have a period of 1 sec., they will have a zero level at a time interval of 4 sec., and in addition the quantity of information stored at the memory capacitor 54 will be zero at this instant. As a result, the signal-altering means under these conditions will operate in such a way that no altering signal will be provided at the signal-transmitting means 44 and the electrical means 45 will be operated at an exposure time determined only by the selected timing resistor of the timing circuit means 42.

Thus, with the above operating example, the signal-altering means has detected that no altering signal is required since the best possible exposure time precisely coincides with the exposure time provided by a selected timing resistor of the timing circuit means 42.

All of the above operations take place just prior to actual tripping of the shutter so that it opens in order to start the exposure. When the shutter switch 46 opens, the shutter also mechanically opens to start the exposure, and the transistor 44 will become conductive in response to the time constant determined by the capacitor 43 and the selected timing resistor of the timing circuit means 42 in accordance with the four operating pulses. Once this signal is transmitted to the electrical means 45 the shutter automatically closes in a well known manner.

If it is now assumed that the intensity of the light at the object to be photographed is 4.5 L.V., then the light responsive circuit means 48 will terminate the operation in 4.5 sec. Thus the switch 66a will now open at an intermediate point between the fourth and fifth operating pulses developed by the oscillating circuit 47, so that actually only four pulses will be transmitted to the electrical selecting means 41. Thus, the same timing resistor will be selected as in the above example where the light intensity was 4 L.V.

The sawtooth signal illustrated in FIG. 7c periodically charges the capacitor 54, so that under these conditions where the operation is terminated at 4.5 sec., the fifth sawtooth signal will be at an intermediate point between its lowest and highest level. Thus, when the switch 55 is changed over to engage contact 55b, there will indeed be an altering signal provided by the signal-altering means and delivered through the transistor 56 thereof to the signal-transmitting means formed by the transistor 44 and the capacitor 43. In this way the timing signal corresponding to the fourth resistor selected from the circuit 42 will be altered in accordance with the quantity stored at the capacitor 54 of the signal-altering means so as to achieve an improved exposure of the film. Also, in this way the circuitry operates to achieve a continuous exposure time adjustment.

Thus, if the circuit 42 is operated by the selecting means 41 so as to select four resistors, so that in the case of an accumulative type of circuit 42 four resistors form the composite resistance corresponding only to 4 L.V., the trigger voltage on the other hand is controlled to receive the additional altering signal corresponding to the additional 0.5 L.V. which cannot be provided by the step-type of time signal circuit 42. As a result the shutter releasing operation takes place in accordance

with 4.5 L.V., or in other words the actual intensity of the light from the object to be photographed.

The upper limit value of the sawtooth signals in FIG. 7c may be determined in accordance with the change in the exposure time adjusting value determined by the selected timing resistors and the capacitor 43. In other words, the upper limit value of the sawtooth signals is known as a variation in the resistances of the timing resistors 42a, 42b, and 42c which have resistances varying in accordance with a multiple proportion.

The variable resistor 61 is included in the light-responsive circuit means 48 which controls the duration of operation as described above in order to introduce into the exposure time determination such factors as the speed of the film which is exposed and the magnitude of the exposure aperture set by the diaphragm. Thus, by operating the variable resistor 61, the switching transistor 65 is adjusted so as to turn on at a predetermined time. For example, one-step operation of variable resistor 61 will turn on the switching transistor 65 at a point when the sawtooth signal is increased by one pulse, thereby controlling the exposure time in accordance with variations in exposure time determining factors in addition to the light intensity.

Referring now to FIG. 8 there is illustrated therein a different embodiment of the operating means and signal-altering means of FIG. 7. In FIG. 8 the operating circuit 47 includes a power source for a small synchronous motor 69, this power source being electrically connected to the light-responsive timing circuit means 48. The oscillating circuit means includes a circular variable resistor 71 which has a rotary slider contact 71b which is coupled through a gear reduction 70 to the synchronous motor 69 so as to be driven thereby. The rotary variable resistor 71 includes the circular resistance 71a along which the slider contact 71b moves in response to the drive from the motor 69. Thus, during each rotation of the slider 71b the resistance value derived from the rotary varibale resistor 71 continuously changes. The signal-altering means includes the amplifying transistor 72 which receives at its base the varying voltage developed by the rotary variable resistor 71. A switching transistor 73 is controlled so as to turn on and off under control of the amplifying transistor 72. A differential circuit is made up of a capacitor 74 and a resistor 75 which are connected between the collector and emitter terminals of the switching transistor 73. The output terminal c of the amplifying transistor 72 which forms the signal-altering means of this embodiment is electrically connected to the base of the transistor 56 of the signal-altering means as shown in FIG. 7a. The electrical selecng means 41 of FIG. 7a receives its operating pulses through a conductor connected to the junction d between capacitor 74 and resistor 75. In this way the operating pulses are transmitted to the selecting means 41. The relay coil 67 shown in FIG. 8 is connected to the light-responsive circuit means 48 in the same way as the relay coil 67 of FIG. 7a. However, in FIG. 8 this relay coil 67 controls the switch 76 so that when the relay coil 67 is operated by the light-responsive means 48, the switch 76 will be controlled.

With the embodiment of FIG. 8, the synchronous motor 69 rotates at a constant speed so that each time the slider 71b makes one complete revolution a sawtooth voltage will be applied to the base of the amplifying transistor 72. Accordingly, the sawtooth pulse sig-

nals as shown in FIG. 7c will appear at the output terminal *c*, and at the same time sharp pulse signals which are differentially processed will appear at the junction *d* at the same frequency as the sawtooth signals, these sharp operating pulses at the junction *d* being similar to those illustrated in FIG. 7b. At the instant when the synchronous motor 69 is disconnected from the power source by operation of the circuit 48, so that the slider 71b is stopped at a position determined by the intensity of the light received from the object to be photographed, the exposure time will be determined. Since the reserve voltage determined by the stopped position of the slider 71b will develop at the terminal *c* an intermediate value of a sawtooth signal, the trigger voltage of the electrical shutter-control system will be controlled in a continuous manner.

Thus, with this embodiment the specific timing resistors of the timing circuit 42 are selected in response to the pulses derived from the oscillating circuit 47 of FIG. 8, and the trigger level of the switching circuit which transmits the signal to the electromagnet 45 will be controlled according to the sawtooth signals. Also, the time limiting circuit 48 will convert the logarithmically converted information from the light received from the object into a time signal arranged so that it is operable to determine the value determined by the pulse signal so as to determine which timing resistors are to be selected. Thus, an exposure time corresponding to the intensity of the light which has a value between the intervals of two adjacent timing resistors will be converted so as to control the trigger voltage, and thus it is possible to provide a continuous adjustment of exposure time with the exposure time signals delivered in a stepwise manner from the timing resistors and the timing capacitor to the signal-transmitting transistor 44.

With the embodiment of FIG. 8 a timing resistor selecting type of electrical shutter-control system, which ordinarily is disadvantageous in that it provides a stepwise adjustment of exposure time, can easily be improved so as to function as a continuous adjustment of exposure time. The provision of the variable resistor 61 in the circuit 48 as shown in FIG. 7a enables control factors to determine the exposure time in accordance with such factors as film speed and diaphragm aperture. In addition, by use of a functional resistor in place of a circular resistor 71a in the oscillating circuit 47, as shown in FIG. 7a, it is possible to develop an ideal sawtooth signal. In these embodiments of FIGS. 7a and 8, although only three timing resistors 42a, 42b, 42c are used, any other desired number of timing resistors may be used as required. In addition, the change-over switch 55 and the switch 66a (or switch 76 in the embodiment of FIG. 8) need not be mechanical switches but may be replaced by any type of contactless elements such as switching transistors.

FIGS. 9 and 13 respectively illustrate embodiments similar to that of FIG. 7a but having signal-altering means capable of altering the exposure-time determining signal in such a way that a correction is made for the non-linear characteristic of the film in the region of low light intensity. Thus, each of these embodiments has a signal-altering means to be used with an electrical shutter-controlling system having a switching circuit which operates in response to time signals developed from an RC timing circuit by selecting a resistor contained therein in accordance with a stepped variation

in the light intensity from the object to be photographed. The signal-altering means alters the stepped type of signal in accordance with light received from the object into periodic signals. A photoelectric circuit 5 forms part of the signal-altering means for altering the signal at a low light intensity region, so that the signal transmitted to the electromagnet is altered in accordance with the film-characteristic compensating signal at a low light intensity region.

10 Referring to FIG. 9, there is illustrated therein the electrical selecting means 81 and the timing circuit means 82 which includes the plurality of timing resistors 82a, 82b, 82c, 82d, and 82e which are connected in parallel with each other. These resistors are respectively connected in series with the switching transistors 82a', 82b', 82c', 82d', and 82e' which are rendered conductive upon receiving a selecting signal from the selecting means 81 so as to supply current to the series-connected timing resistors 82a, 82b, 82c, 82d or 82e. Each timing resistor is connected in series with the capacitor 83 to form a timing circuit therewith.

20 The timing resistors 82a-82e may be arranged either so as to be sequentially selected with only one of the resistors operating at a given time, or they may be operated accumulatively so that the successive selected transistors are connected in parallel and form a single composite resistor. The signal-transmitting means 25 includes, in addition to the capacitor 83, the transistor 84 which is a switching transistor having the electromagnet 85 in its collector circuit so as to form the electrical means for initiating the shutter-closing operations when a signal is transmitted from the signal-transmitting means 83, 84 to the electrical means 85. A normally closed shutter release switch 86 short-circuits or bypasses the capacitor 83, this switch 86 being automatically opened upon depression of the shutter-operating plunger, as described above.

30 The above structure is the principal portion of a known timing resistor selecting type of electrical shutter-control system. The added features of the present invention are described below. With the embodiment of FIG. 9 the operating means for operating the selecting means 81 also takes the form of an oscillating circuit and in this embodiment also there is a light-responsive circuit 88 which determines the duration of the operation of the oscillating circuit 87. The light-responsive circuit 88 converts the logarithmically converted information in accordance with the light received from the object to be photographed into a time signal.

35 The principal part of the oscillating circuit 87 includes the timing circuit made up of the variable resistor 89 and series-connected capacitor 90, these components being electrically connected to the power source 91. This oscillating circuit includes the unijunction transistor 92 connected at its emitter to a junction between the resistor 89 and capacitor 90. The signal-altering means includes a buffer transistor 93 connected at its base to the junction between the resistor 40 89 and the capacitor 90. This signal-altering means includes the memory capacitor 94 connected to the output terminal *b* of the buffer transistor 93. The output terminal or the first base *a* of UJT 92 is electrically connected to the electrical selecting means 81 so that the pulses appearing at the terminal *a* are transmitted to the timing resistor selecting circuit of the selecting means 81 so as to select in this way an appropriate tim-

ing resistor 82a, 82b, 82c, 82d or 82e. The memory capacitor 94 is connected to the output terminal *b* of transistor 93 and is electrically connected to the common terminal 95c of the change-over switch 95 so as to be electrically connected with the output terminal *b* through the normally closed terminal 95a of the switch 95. This switch has a normally open terminal 95b connected to the base of the transistor 96 of the signal-altering means so as to alter the signal derived from the circuit 82 in order to control the trigger level. In this way the trigger level of the switching transistor 84 is controlled depending upon the electrical quantity stored at the memory capacitor 94. The emitter terminals of transistors 84 and 96 are connected in common with a trigger transistor 97.

It is to be noted that the oscillating frequency of the oscillating circuit 87 need not be set at any fixed value but may be set at an optional value as long as it maintains a constant relation with the light received from the object to be photographed. Thus, the logarithmically converted information of the light received from the object to be photographed is conditioned at the same period as the oscillating information which continues at equal and constant intervals. As long as this condition is satisfied the oscillating frequency may be determined in such a way that the period of 1 sec. corresponds, for example, to 1 L.V.

The intensity of the light received from the object to be photographed is conditioned at an equal and constant interval by converting it logarithmically. In order to further convert the logarithmically converted information into the time limiting signal, which limits the operating duration, the light-responsive circuit means 88 is provided. This circuit means 88 includes a buffer transistor 100 connected at its base to a junction between the series-connected photosensitive component 98 and logarithmic conversion diode 99. A transistor 102 is connected through the variable resistor 101 to the emitter of the buffer transistor 100. A transistor 103 has its internal resistance varied under the control of the transistor 102. A timing capacitor 104 is connected to the collector of transistor 103. The transistor 103 with the capacitor 104 forms a timing circuit. A switching transistor 105 is arranged in such a way that it operates under the action of this timing circuit. In the collector circuit of the switching transistor 105 is inserted a relay coil 106 which operates the switches 95 and 107. The switch 107 is a normally closed switch inserted between the terminal *a* of UJT 92 and the electrical selecting means 81. A power source switch 108, closed during initial increment of movement of the shutter-releasing plunger, is connected in the circuit of the power source 91.

In order to be able to compensate for non-linear film characteristic at the lower light intensity region, the signal-altering means of FIG. 9 includes a transistor 109 connected at its emitter to the trigger resistor 97. This transistor 109 is connected at its base to a junction between a photosensitive element 110 and a divider resistor 111.

Thus, the transistor 109, the photosensitive element 110, and the divider resistor 111 together form a photoelectric conversion section 112 which forms part of the signal-altering means of FIG. 9 to develop a compensating signal in the lower light intensity region of the light received from the object to be photographed.

The operation of the circuitry of FIG. 9 is similar to that of FIG. 7a, and the trigger voltage of the signal-transmitting or switching circuit is controlled by the sawtooth periodic signals so as to achieve a continuously adjustable exposure time as described above.

The portion 112 of the signal-altering means of FIG. 9 which functions to compensate for the non-linear film characteristic operates as follows:

When the intensity of the light is in the lower light intensity region, the internal resistance of the photosensitive element 110 will increase so as to render the transistor 109 conductive under these conditions. The transistor 109 which becomes conductive under these low light intensity conditions serves to regulate the collector-emitter current depending upon the intensity of the light at the lower light intensity region and acts to raise the voltage lowered by the trigger resistor 97 connected to the emitter terminal of the resistor 109. More specifically, the time-conditioned synchronized signals and the compensating information derived from the photoelectric conversion section 112 are combined at the trigger resistor 97 and control the trigger voltage of the switching transistor 84 which forms part of the signal-transmitting means for transmitting the signal to the electrical means 85 which initiates the shutter-closing operations in response to this transmitted signal.

The compensating portion of the altering signal which provides the compensation for the non-linear film characteristic is illustrated by the dotted line Y in FIG. 11. Since the exposure time is prolonged in proportion to this compensating signal, it will be possible to make a photograph in conformity with the film characteristics at the lower light intensity region.

FIG. 10 illustrates another embodiment of the portion 112 of the signal-altering means. This portion 112 of FIG. 10 differs from that of FIG. 9 in that instead of the resistor 111 of FIG. 9 a second photosensitive element 113 is connected in series with the photosensitive element 110 when the transistor 109 connected to the junction between the series connected photosensitive components 110 and 113.

FIG. 12 shows at the dotted line Y the compensating signal obtained with the section 112 of FIG. 10. As may be seen from FIG. 12, the angle θ of the line Y of FIG. 12 is considerably less steep than the corresponding angle shown in FIG. 11 for the embodiment of FIG. 9. In this way a sudden change in the trigger voltage with a change in the intensity of the light received from the object may be prevented. The characteristic curve Y of the compensating signal as shown in FIG. 12 is achieved by the use of the two photosensitive elements 110 and 113 which have different γ - values and an equal resistance when they receive no light. The inclination angle θ , however, may be changed to any desired angle with variation of the γ values.

The embodiment of FIG. 13 is constructed so that the part of the altering signal which compensates for the film characteristic is added to the periodic signals. For this purpose, the base of the transistor 93 of the signal-altering means is electrically connected through a diode 114 to a junction between the pair of photosensitive elements 110 and 113 which are connected into the circuit in the manner shown in FIG. 13. The series-connected photosensitive elements 110 and 113 of FIG. 13 are electrically connected to the base of transistor 93 through the diode 114 in such a way that the latter is coupled at its negative terminal to the transis-

tor 93 and serves to prevent the periodic signals from the oscillating circuit from being discharged from the emitter of UJT 92 to the photosensitive element 110.

In this embodiment a predetermined periodic signal is transferred from the emitter of UJT 92 to the base of transistor 93. In the lower light intensity region, since the base potential is raised by the action of the photosensitive elements 113 and 110, the upper limit value of the periodic signals will be increased due to the reduction in the intensity of light received from the object, and the sawtooth signals derived in this way are illustrated in FIG. 14. Thus, as is apparent from FIG. 14, in the lower light intensity region the trigger voltage is raised by the periodic signals so that the exposure time will be prolonged in order to compensate for the characteristics of the film which is exposed.

With the embodiment of FIG. 9 the switching circuit and the photoelectric conversion section are constructed to form a single circuit arrangement. This requires complicated procedures in order to make an adjustment between the two sections. However, with the embodiment of FIG. 13, the incorporation of the film-characteristic compensating circuitry directly into the oscillating circuit enables an easy adjustment between the two sections to be carried out.

With the above embodiments a timing resistor selecting type of electrical shutter-control system is provided which assures that the exposure will be in conformance with the film characteristics even in a low light intensity region, thereby preventing underexposed negatives from being made, as is often the case when making exposures at low light intensity. Therefore with the electric shutter-control system of this embodiment, the same photographic conditions as in the immediate light intensity region are obtainable even in the lower light intensity region. As a result this embodiment is particularly advantageous when making photographs in theatres or the like where it is not possible to use flash illumination. In addition, these embodiments include the portion of the signal-altering means for continuously adjusting the exposure time when using a timing resistor selecting type of electrical shutter-control device, in this case a relatively simple structure is provided. This latter feature is of advantage in that the structure can easily be accommodated in a camera housing which has only a limited interior space.

Thus, these embodiments of FIGS. 9, 10 and 13 provide an exposure time which is extended in accordance with the light intensity in the lower light intensity region. However, when these embodiments are to be used in an exposure time controlling means of an inexpensive camera, these embodiments are constructed in such a way that they will provide an exposure time which is extended to a predetermined extent when taking photographs in the case where the light intensity is below a predetermined relatively low light intensity.

By replacing the photosensitive elements 110 and 113 of FIG. 13 with each other, a means is provided for automatically compensating for the exposure time, and this means is operable in a higher light intensity region according to the same principle of the invention as described above. Furthermore, if the photoelectric conversion section operates in the medium light intensity region and provides any disadvantageous effects, a separate electronic timer circuit may be added to allow in this way the photoelectric conversion section to start

operation only when the light intensity is reduced below a predetermined value.

FIG. 15 is a wiring diagram of a shutter-controlling system also capable of achieving a continuous adjustment of the exposure time. In this embodiment also the operating means for operating the selecting means takes the form of an oscillating circuit and the signal-altering means is operated by the oscillating circuit with the latter generating the operating pulses which are transmitted to the selecting means and the sawtooth signals which are generated at the signal-altering means. These signals are generated in response to logarithmically converted information from the light which is received from the object to be photographed. The pulses transmitted from the oscillating circuit to the selecting means are relatively narrow, while the sawtooth pulses coincide with the period of the narrow pulses transmitted to the selecting circuit, the sawtooth pulses having amplitudes determined in accordance with the change in the exposure time adjusting values which are determined at each selection of a specific timing resistor in the timing circuit. The operating pulses are thus delivered to the selecting means to select an appropriate timing resistor, and the sawtooth pulses are transmitted to a memory means of the signal-altering circuit to provide charging and discharging of the memory means. With this embodiment there is a time-limiting circuit which limits the duration of operation of the oscillating circuit and signal-altering means, but in this embodiment the time-limiting circuit provides a predetermined duration of operation irrespective of the lighting conditions while the photosensitive means or light-responsive circuit is incorporated into the oscillating circuit.

Referring to FIG. 15, it will be seen that the electrical selecting means 121 is made up of a pulse counter circuit or the like. This selecting means 121 is electrically connected to the timing circuit means 122 which includes the plurality of timing resistors 122a, 122b, and 122c which are connected in parallel with each other. These timing resistors are respectively connected in series with the switching transistors 122a', 122b', and 122c', the bases of which are connected to the selecting means 121 to thereby receive a selecting signal depending upon the operating pulses. In order to condition the intensity of the light received from the object in accordance with a multiple proportion, the resistances of the timing resistors 122a, 122b, and 122c are determined in accordance with the same multiple proportion. A timing capacitor 123 forms part of the signal-transmitting means and forms a timing circuit together with a selected timing resistor, thereby producing the timing signal which is required for determining the exposure time in accordance with the multiple proportion. The signal-transmitting means also includes the switching transistor 124 which is constructed so as to carry out a switching operation in response to the timing signal. In the collector of the transistor 124 is inserted the electromagnet 125 which when receiving the signal from the signal-transmitting means responds to initiate the shutter-closing operations. The circuitry includes the normally closed shutter-releasing switch 126 which is opened upon depression of the shutter-tripping button.

The above portion of the circuitry of FIG. 15 forms a known timing resistor selecting type of electrical shutter-control system. The oscillating circuit and time-

limiting circuit as well as the signal-altering means, are described below.

The oscillating circuit 127 includes the logarithmic conversion diode 129 which is connected in series with the photosensitive element 128. To a junction between the series-connected components 128 and 129 is connected the base terminal of an amplifying transistor 130 the emitter of which is electrically connected to the base of a transistor 132 through a variable resistor 131 which is adjustable to introduce such factors as the speed of the film and the size of the exposure aperture. A transistor 133 which constitutes a timing circuit is arranged to be controlled by the transistor 132 and is electrically connected at its collector to a timing capacitor 134. A unijunction transistor 135 is connected at its emitter to the positive terminal of the timing capacitor 134 and has an output terminal *a* at its first base electrically connected through a conductor 136 to the selecting means 121 so as to transmit operating pulses thereto. The base of the buffer transistor 137, which forms part of the signal-altering means, is electrically connected to the positive terminal of the timing capacitor 134. The output terminal *b* of the emitter of the buffer transistor 137 is electrically connected to the memory capacitor 138 of the signal-altering means through the normally closed contact 139*a* of the switch 139. The normally open terminal 139*b* of the change-over switch 139 is electrically connected through a conductor 141 to the base of the transistor 140 of the signal-altering means. Thus, through this transistor 140 the signal to be transmitted to the electrical means 125 from the transistor 124 is altered in a manner similar to that described above. The emitter of the transistor 140 is connected to a trigger controlling resistor 142 so as to control in this way the trigger voltage of the transistor 124 which also is connected at its emitter to the trigger controlling resistor 142.

The time-limiting circuit 143 includes a variable resistor 144 and a timing capacitor 150 which are connected in series. A pair of relay coils 146 and 147 are inserted in the collector circuit of transistor 145 the base of which is electrically connected to a junction between the resistor 144 and the capacitor 150. The relay coil 146 controls the change-over switch 139 while the relay coil 147 controls the switch 147*a* in the conductor 136. The circuit of FIG. 15 includes the power source 148 and the power source switch 149.

With the embodiment of FIG. 15, when the power source switch 149 is closed during an initial part of the movement of the shutter-releasing plunger of the camera, the photosensitive element 128 will provide a signal corresponding to the intensity of the light received from the object to be photographed. This signal is logarithmically converted by the diode 129. Inasmuch as all of the transistors 130, 132, and 133 which receive the logarithmically converted signal become conductive, the timing capacitor 134 will be charged in accordance with the variation in the internal resistance of the transistor 133. As a result, UJT 135 will be temporarily turned on due to the rise in voltage at its emitter, so as to thereby form a discharge circuit for the timing capacitor 134. At this time the pulse signal as illustrated in FIG. 16*a* will be developed at the output terminal *a* to be transmitted to the selecting means 121 through the conductor 136. In response to the first operating pulse the selecting means 121 turns on the transistor 122*a*', so as to select the timing resistor 122*a*. On the

other hand, because the positive side of the timing capacitor 134 will be charged as time passes, the sawtooth pulses shown in FIGS. 16*b*, 16*c*, and 16*d* will be developed at the output terminal *b* of the buffer transistor 137 of the signal-altering means. Thus, the memory capacitor 138 of the signal-altering means will be charged and discharged in response to these sawtooth pulses.

The oscillating circuit 127 cyclically repeats these operations continuously, and the periods of oscillation will have equal intervals due to the logarithmic conversion of the light received from the object to be photographed. The amplitude of the sawtooth signals is determined in accordance with the exposure adjusting value which varies in accordance with a multiple proportion. The upper limit value of the amplitude will be constant irrespective of the intensity of the light received from the object to be photographed.

When the power source switch 149 is closed, the time-limiting circuit 143 operates the variable resistor 144 and the timing capacitor 150 irrespective of the intensity of the light received from the object. The transistor 145, therefore, will be turned on after a predetermined interval determined by the time constant which is obtained in this way. As a result, the relays 146 and 147 will be energized and the change-over switch 139 will make contact with the normally open contact 139*b* while the contact 139*a* will become open, thereby terminating the operation of the oscillating circuit so that the pulse signals delivered to the selecting means and the sawtooth signals of the signal-altering means will terminate. Assuming now that the oscillating period of UJT 135 is set to a value corresponding to 1 L.V. and the actual intensity of the light received from the object is equal to 3 L.V., then the circuitry will develop three pulses at the output terminal *a* and three timing resistors 122*a*, 122*b*, and 122*c* will be accordingly selected. At the output terminal *b*, on the other hand, three sawtooth pulse signals will be developed as illustrated in FIG. 16*b* to charge and discharge the memory capacitor 138. However, when the time-limiting circuit 143 operates, to terminate the operation precisely at the end of three seconds in this particular example, the level of the sawtooth signal will be precisely at zero and memory capacitor 138 will possess no charge. Thus, the change-over of the switch 139 will not transmit any altering signal under these conditions to the transistor 124, since under this particular set of operating conditions the timing signal derived from the timing circuit 122 precisely equals the exposure time called for by the particular operating conditions.

Under these conditions, depression of the shutter button will open the shutter mechanically, and at the same time the switch 126 will open so as to permit the shutter-closing operations, in accordance with the exposure time adjusting signal developed by the delay circuit formed by the capacitor 150 and the selected timing resistors 122*a*, 122*b*, and 122*c* to take place.

FIGS. 16*a* and 16*c* respectively represent the pulse signals delivered to the selecting means 121 and the sawtooth signals at the signal-altering means which are developed when the intensity of the light corresponds to 4 L.V.

When the intensity of the light includes a fractional value, such as a light intensity of 3.5 L.V., three pulses will be developed at the output terminal *a* to thereby select the three timing resistors 122*a*, 122*b*, and

122c. However, during the duration of operation determined by the time-limiting circuit means 143, the sawtooth signals will have a configuration as illustrated in FIG. 16d, and therefore the memory capacitor 138 will retain a certain amount of charge which is stored therein at the instant when the operation is terminated by the circuit means 143. Therefore, the terminal voltage of the memory capacitor 138 will be applied across the base and emitter of the transistor 140 of the signal-altering means so as to alter the signal of the transistor 124 of the signal-transmitting means, this altering of the signal taking place by controlling the trigger voltage of the switching transistor 124 by way of the trigger control resistor 142.

When the shutter-tripping plunger is depressed, the exposure time will be adjusted both by the timing signal from the selected timing resistors 122a, 122b, and 122c and the capacitor 123 together with the controlled trigger voltage, thereby achieving a shutter operation in accordance with the light value of 3.5 L.V. or the actual intensity of the light. The same considerations apply to any photographing conditions where the intensity of the light from the object, corresponds to such values as 3.1 L.V., 3.2 L.V., 3.3 L.V., etc. to thereby permit the continuous adjustment of exposure time.

Thus, with the embodiment of FIG. 15 the operating pulses transmitted to the selecting means and the sawtooth signals of the signal-altering means are developed in accordance with the logarithmically converted information of the light received from the object within the operating range of the timer circuit means 122 in order to select an appropriate timing resistor depending upon the operating pulses and to control the trigger voltage of the switching circuit by altering the timing signal from the selected timing resistor with the signal-altering means which controls the trigger voltage by way of the interposed memory capacitor 138 which in turn is operated by the sawtooth signals. Thus, the continuous adjustment of the exposure time is achieved even when the exposure time corresponds to an interval between any two adjacent exposure time adjusting values determined by the selection of the specific timing resistors of the timing circuit means 122.

It is to be noted that the variable resistor 131 in the oscillating circuit 127 permits an optional change of the period between the operating pulses and the sawtooth signals. In other words through adjustment of this variable resistor the frequency of the operating pulses and sawtooth signals can be regulated. In addition, the variable resistor 131 also serves to vary the logarithmically converted information. Thus, the extended range of control for exposure factors such as film speed, diaphragm aperture, and the like can be achieved.

Although in the embodiment of FIG. 15 there are illustrated only three timing resistors, any desired number of timing resistors may be provided. Also, the illustrated relays 146 and 147 may be replaced by other switching elements such as switching elements of semiconductor type.

FIGS. 17, 19, 20 and 21 respectively illustrate circuits of electrical shutter-control systems which also enable a continuous adjustment of the exposure time to be brought about. With the systems of these embodiments the exposure time adjusting signal to be developed by the timing value developing circuitry includes the timing resistors of the timing circuit means and the signal-transmitting means which includes a timing ca-

pacitor controlled directly with one or more of the selected timing resistors in accordance with the intensity of the light received from the object to be photographed. These embodiments include a timing value developing circuitry which selectively determines the resistance of the RC timing circuit in accordance with the stepped values of the intensity of the light. The signal-altering means for handling fractional signals of light intensity, which cannot be covered by the selection of the timing resistors, is included in the circuitry to develop the periodic signals. With these embodiments the charging circuit of the timing value developing part of the system has a current regulating element such as a transistor whose current regulating action is controlled by the periodic signals of the signal-altering means. Alternatively, the charging circuit may have inserted therein a current regulating element such as a photosensitive element arranged so that the light received thereby may be controlled by means of the periodic signals of the signal-altering means. Furthermore, in the discharge circuit of the timing circuitry there may be inserted a current regulating element such as a transistor whose current regulating action is controlled by the periodic signals of the signal-altering means. In addition, it is possible to situate in the discharge circuit of the timing circuitry a photosensitive element which is controlled with respect to the amount of light received thereby by means of the periodic signals, so as to allow in this way the photosensitive element to perform the function of a current regulating device.

Referring now to FIG. 17, the shutter-controlling system illustrated therein includes a timing resistor selecting type of electrical shutter-control device having a timing value developing means. Thus, this circuitry includes the electrical selecting means 155 which is operated by an operating means which includes a photosensitive element 151 connected in series to a bleeder resistor 152, these components 151 and 152 being connected in series with each other and with the power source 154 through the power source switch 153. The electrical selecting means 155 primarily consists of a pulse counter circuit and develops a selecting signal in accordance with the divided voltage from the photosensitive element 151 and the bleeder resistor 152, this selecting means 155 being connected to a junction between the series connected components 151 and 152. Thus, the selecting means 155 will intermittently transfer selecting signals to the switching transistors 156a', 156b', and 156c' which are included in the timing circuit means 156. The timing resistors 156a, 156b, and 156c are respectively connected in series with the latter transistors and form the timing value developing circuit. These timing resistors have different resistances one with respect to the other, and the difference between their resistances is such that the timing resistors when connected to the capacitor 157 provide different time constants for developing the exposure time adjusting information which varies in accordance with a multiple proportion.

The signal-transmitting means of FIG. 17 includes in addition to the capacitor 157, the switching transistor 158 which turns on in response to receiving a certain level of terminal voltage across the timing capacitor 157. In the collector circuit of the transistor 158 is inserted the electromagnet 159 which forms the electrical means of this embodiment for initiating the shutter-closing operations in response to receiving a signal

from the signal-transmitting means 157, 158. A shutter release switch 160 is normally closed so as to short circuit the capacitor 157. This switch 160 is automatically opened upon depression of the shutter-tripping button of the camera.

A signal-altering means 161 is provided for converting the information with respect to the intensity of the light which corresponds to an interval between the steps which can be selected by the timing circuit means 156. The signal-altering means 161 includes the timing resistors 161a, 161b, and 161c which are connected in parallel with each other and which are supplied with electrical current in synchronism with the selecting operation by the selecting means 155 in order to select the timing resistors 156a, 156b, and 156c. These resistors of the signal-altering means 161 are connected in series with a photosensitive element 162. A transistor 163 is included in the electrical signal-altering means 161 in such a way that it receives at its base the terminal voltage of the parallel circuit. The emitter of the transistor 163 is electrically connected to an output resistor 164 to which the memory capacitor 165 is connected by way of the change-over switch 166. The circuit 161 also includes the switching transistors 161a', 161b', and 161c' which determine the supply of electrical current to the several timing resistors 161a, 161b, and 161c, respectively.

The resistance values of the timing resistors 161a, 161b, and 161c are selected with respect to the intensity of the light conditioned by the timing resistors 156a, 156b, and 156c. In other words, the resistance of the resistor 161a, is set in correspondence with the difference between the adjusting value determined by selection of timing resistor 156b and the adjusting value determined by selection of the timing resistor 156a. Similarly, the resistance value of timing resistor 161b corresponds to the difference between two adjusting values respectively determined by the timing resistors 156c and 156b. The resistance of timing resistor 161c corresponds to the difference between the two values which are respectively determined by the timing resistor 156c and any subsequent resistor, in the event that the circuitry includes such a subsequent resistor.

When the timing resistor 156a is selected by the electrical selecting means 155, the electrical current will be supplied to the timing resistor 161a. When the intensity of the light is such that it can be completely converted by, or in other words corresponds precisely to the timing value achieved by the timing resistor 156a, there will be no development of potential at the junction *a* between the timing resistor 161a and the photosensitive element 162. However, when the intensity of the light reaches a value close to that which may coincide with the value determined by the timing resistor 156b, the potential at the connecting point *a* will rise to a maximum value. When the intensity of the light continues to increase until the timing resistor 156b is selected, the electrical current will be supplied to the timing resistor 161b. The result is a sudden reduction of potential at the junction *a* to almost zero potential. The same considerations apply also to the timing resistors 156b and 156c.

FIG. 18 illustrates the inclined sawtooth voltage curve which corresponds to the above-described operation. The upper limit value of the inclined sawtooth voltage pulses is a constant determined by the difference between any two adjacent adjusting values, each

in turn being determined by the two selected values, whereas an intermediate value along an inclined voltage curve is determined by the light responsive element 162 which operates in response to the light received from the object.

The memory capacitor 165 of the signal-altering means 161 is charged and discharged through the normally closed terminal 166a of the change-over switch 166, and the charge stored at the memory capacitor 165 is applied to the base of the amplifying transistor 167 through the normally open terminal 166b of the switch 166 when the latter is changed over to engage the terminal 166b. In the collector circuit of the amplifying transistor 167 there is located a meter or moving coil 168 which mechanically actuates a diaphragm mechanism 170 situated in front of a photosensitive element 169, so that the extent to which the diaphragm 170 is opened will control the amount of light received by the photosensitive element 169. This photosensitive element 169 is connected in parallel with the capacitor 157 of the signal-transmitting means. Thus, the extent to which the timing capacitor 157 is charged and discharged is controlled by way of the photosensitive element 169 in accordance with the light received thereby as determined by the transistor 167 and moving coil 168.

Thus, with the embodiment of FIG. 17 the altering signal is applied to the capacitor 157 of the signal-transmitting means 157, 158. With the embodiment of FIG. 17 when the switch 153 is closed prior to release of the shutter, an appropriate timing resistor of the timing circuit 156 will be selected in accordance with the intensity of the light. However, since the shutter-release switch 160 is still closed at this time, the capacitor 157 is not charged and the shutter is not actuated.

For purposes of illustration if it is assumed that the timing resistors 156a, 156b, and 156c are selected in correspondence with 1 L.V., 2 L.V. and 3 L.V., respectively, and if it is assumed that the diaphragm 170 is fully opened at the lower limit value of each of the inclined voltage pulses, when the charge of the memory capacitor 165 is at a minimum, then the operation set forth below will follow. In addition it is assumed that the timing resistor selecting means 155 is adjusted in such a way that the timing resistor 156b is selected for 1 L.V. the timing resistor 156c for 2 L.V., and so on.

If now the actual intensity of light is 1 L.V., timing resistor 156b will be selected and at the same time the current will be supplied to the timing resistor 161b, while the diaphragm 170 remains fully opened as pointed out above. Upon depression of the shutter button so that the shutter release switch 160 opens, the shutter is mechanically opened and the transient voltage of timing resistor 156b will be used to charge the timing capacitor 157. In this event, however, it is to be noted that all of the transient voltage is charged in the timing capacitor 157 and the transient voltage corresponding to 1 L.V. will flow in the light sensitive element 169. As a consequence, the timing resistor 156b will be selected and the adjusting value obtained will correspond to 1 L.V.

On the other hand, if the intensity of light received from the object to be photographed corresponds to 1.5 L.V., the charge stored in the memory capacitor 165 will correspond to an intermediate value of the inclined voltage as illustrated in FIG. 18, so that the diaphragm mechanism 170 will be controlled to provide a dia-

phragm aperture on the order of 50 percent of the full aperture. In more detail, when the actual intensity of light is 1.5 L.V., the timing resistor 156b is selected and therefore some portion of the transient voltage corresponding to 0.5 L.V. will flow in the light sensitive element 169. As a consequence, the resulting adjusting value will correspond to 1.5 L.V. These operating steps are carried out continuously and accordingly a continuous adjustment of exposure time will be effected with this embodiment.

FIG. 19 illustrates a modification of that part of the signal-altering means which controls the charge of the capacitor 157. Thus, in FIG. 19 the current regulating circuit which includes the light sensitive element 169 of FIG. 17 is replaced by a transistor. More specifically, the embodiment of FIG. 19 is constructed in such a way that the inclined voltage of the signal-altering means is applied from the change-over switch 166 to the base of a transistor 171. In principle, this embodiment is equivalent to that of FIG. 17, but the current flowing in the transistor 171 will be the same no matter which of the timing resistors 156a, 156b, and 156c has been selected. The resulting adjusting value will therefore have a small degree of error and an almost continuous adjusting value will be obtained. Thus, the embodiment of FIG. 19 may be used in a less expensive camera which requires a high degree of accuracy.

FIG. 20 illustrates a further modification of the part of the signal-altering means which control the charge of the capacitor 157 of the signal-transmitting means. With the embodiment of FIG. 20 the photosensitive element 169 of FIG. 17 is connected in series with the charging circuit of the capacitor 157. With the embodiment of FIG. 20 the diaphragm mechanism 170 is constructed in such a way that it provides a minimum diaphragm aperture when the charge stored in memory capacitor 165 is at its lower limit value corresponding to the lower limit of the inclined voltage pulses of FIG. 18, and the sum of the resistance of timing resistor selected by the selecting means and the internal resistance of the photosensitive element 169 provides a highly accurate timing resistance. For example this embodiment is arranged in such a way that an adjusting value corresponding to 1 L.V. can be obtained in response to the capacity of the timing capacitor 157 and to the sum of the resistance of the selected resistor of the timing circuit 156 and the internal resistance of the light sensitive element 169 at the time when the diaphragm mechanism 170 provides a minimum diaphragm aperture. This is true irrespective of which of the timing resistors of the timing circuit 156 is selected.

With this example, therefore, if the timing resistor 156a is selected corresponding to a light intensity of 1 L.V. simultaneously with the supply of current to the timing resistor 161a, then when the light intensity is of such a value that there is no fractional addition to be made so that the best possible exposure will be made simply by the selection of the resistor 156a, then the quantity of charge stored in capacitor 165 will be zero. Thus, under these conditions the diaphragm mechanism 170 will remain unchanged and it will maintain its minimum diaphragm aperture even if the changeover switch 166 is actuated. Thus, the resistance of the timing resistor 156a, the internal resistance of light sensitive element 169 and the capacity of timing capacitor 157 will determine an exposure time corresponding to 1 L.V., in this particular example.

If, however, the intensity of light received from the object corresponds to 1.5 L.V., then the memory capacitor 165 will be charged correspondingly with a magnitude corresponding to the fractional value of 0.5 L.V. Thus the diaphragm mechanism 170 will now provide an appropriate diaphragm aperture upon switching over of the change-over switch 166. This aperture corresponds to the fractional L.V., and therefore the internal resistance of light sensitive element 169 will be reduced accordingly. As a result, even if the intensity of light is 1.5 L.V., an adjusting value corresponding thereto will be determined by the time constant determined by the resistance of the selected timing resistor 156a, the internal resistance of light sensitive element 169, and the timing capacitor 157. This operation is also true in connection with the timing resistors 156b and 156c. Thus, the diaphragm mechanism 170 can be controlled continuously in accordance with the intensity of light, thereby achieving a continuous adjustment of exposure time.

FIG. 21 illustrates a circuit of a further modification of FIG. 20 where a transistor 171 is used as a current regulating element instead of the light-responsive element 169. In the embodiment of FIG. 21 the transistor 172 receives directly the voltage stored in the memory capacitor 165 and, accordingly, will more or less adjust the achieved value. In principle the embodiment of FIG. 21 is equivalent to that of FIG. 20.

As discussed above, the embodiments shown in FIG. 17, 19, 20 and 21 include elements such as a light sensitive element or transistor arranged in the charge and discharge circuit of the adjusting value developing timing circuitry which is included in the electrical shutter-control system to achieve an exposure time adjusting value in a stepwise manner, and the incident light received by the photosensitive element in the case of FIGS. 17 and 20 is controlled by means of the periodic signals corresponding to the variation in the exposure time adjusting values which vary in a stepped manner. Thus, the current regulating action of the photosensitive element can be determined depending upon the periodic signals as well as the intensity of the light received from the object, so that a continuous conversion of the exposure time signals from the predetermined values developed by the circuitry 156 can be achieved. By incorporating one of the embodiments of FIGS. 17 and 19-21 in a timing resistor selecting type of electrical shutter-control system, it is possible to obtain a series of continuous exposure time adjusting values.

As an alternative to the embodiment of FIGS. 17 and 20, it is of course possible to use instead of the light-sensitive element a transistor situated in the charge and discharge circuit of the timing circuitry which determines the exposure time, and by controlling the current regulating element such as this transistor with the periodic signals of the signal-altering means a nearly continuous adjustment of exposure time is achieved while using a timing resistor selecting type of electrical shutter-control system. In particular, less expensive cameras with less precision can be produced by incorporating the transistors of FIGS. 19 or 21.

In the above embodiment of FIGS. 17 and 19-21 only three timing resistors 157a, 156b, 156c are used, but any desired number of such transistors may be used, and in addition the illustrated switching transistors 156a' 156b' and 156c' as well as the transistors

161a', **b' and 161c' may be replaced by relays, respectively.

The selecting circuits which form the several selecting means 3, 23, 41, 81, 121, and 155 of the above-described embodiment of the invention may have the construction of the selecting circuits shown in U.S. Pat. No. 3,603,799.

It is thus apparent from the above description and drawings that with the present invention it is possible to achieve a continuous adjustment of exposure time with a time resistor selecting type of digital system, so that in this way there is a solution to the conventional problems involved with internal light-receiving systems where the shutter is controlled electrically, and the solution achieved with the present invention is exceedingly simple and highly effective. In addition, as is apparent from the above description, it is possible with the invention to correct the exposure time so as to compensate for the characteristics of the film both in the lower and higher light intensity regions, so that under exposed or over exposed negatives may be avoided.

What is claimed is:

1. For use in a camera, an electrical shutter-control system comprising electrical means for responding to a signal for initiating shutter-closing operations, signal-transmitting means electrically connected with said electrical means for transmitting said signal thereto, timing circuit means electrically connected with said signal-transmitting means for delivering to the latter, to form at least part of the signal transmitted thereby, to said electrical means, one of a plurality of timing signals which differ from each other by increments corresponding to different time intervals, electrical selecting means electrically connected with said timing circuit means for selecting from the latter, to be delivered to said signal-transmitting means, that one of said plurality of timing signals which will provide the best exposure, electrical operating means electrically connected with said selecting means for operating the latter to select said one timing signal, and electrical signal-altering means for automatically detecting when the photographing conditions require a change in said one timing signal to improve the exposure and for determining the extent to which said one timing signal should be changed to improve the exposure, said signal-altering means being electrically connected with said signal-transmitting means for altering said one timing signal received thereby to the extent determined by said signal-altering means before a signal is transmitted by said signal-transmitting means to said electrical means for initiating shutter-closing operations, whereby the latter electrical means will receive a timing signal which, if necessary, is altered to improve the exposure.

2. The combination of claim 1 and wherein said signal-altering means automatically detects when said timing signal should be altered to correspond to a time interval between the intervals corresponding to said increments to cooperate with said timing circuit means for achieving a continuously adjustable exposure time signal for said electrical means which initiates the shutter-closing operations.

3. The combination of claim 1 and wherein said signal-altering means automatically detects when the timing signal should be altered to conform more closely to the characteristics of the film which is exposed.

4. The combination of claim 1 and wherein said signal-altering means detects on the one hand when said

one timing signal should be altered to provide a signal corresponding to a time interval between those corresponding to said increments, to achieve a continuous exposure-time control, and on the other hand to detect when said one timing signal should be altered in accordance with the characteristics of the film which is exposed, for altering said one timing signal in accordance with both of the latter factors.

5. The combination of claim 1 and wherein said signal-transmitting means includes a pair of electrical components one of which is a transistor and the other of which is a capacitor, said signal-altering means being electrically connected with said transistor.

6. The combination of claim 1 and wherein said signal-transmitting means includes a pair of components one of which is a transistor and the other of which is a capacitor, said signal-altering means being electrically connected with said capacitor.

7. The combination of claim 1 and wherein said operating means includes a light-responsive circuit electrically connected with said selecting means for operating the latter in response to lighting conditions, said signal-altering means being electrically connected with said selecting means to be operated thereby also for selecting one of a plurality of signals, said signal-altering means including a light-responsive means for altering the signal of said signal-altering means selected by said selecting means, and said signal-altering means further including a capacitor means to be charged with a charge corresponding to the required alteration of said one timing signal, said capacitor means being electrically connected to said signal-transmitting means for altering said one timing signal, if necessary.

8. The combination of claim 7 and wherein said signal-altering means includes a plurality of parallel-connected circuits one of which is selected by said selecting means, said circuits respectively corresponding to different ranges of light intensity and respectively including resistors which in light ranges where the film in the camera does not respond linearly to change in light intensity provide resistance values which will automatically compensate for the characteristics of the film.

9. The combination of claim 1 and wherein said operating means includes an oscillating circuit means electrically connected with said selecting means for cyclically delivering operating pulses thereto, said signal-altering means including a memory circuit means for cyclically storing electrical quantities corresponding to fractions of said time intervals occurring between said operating pulses, and light-responsive circuit means electrically connected with said operating means for determining the duration of operation thereof, said light-responsive circuit means also being connected with said signal-altering means for actuating the latter to transmit to said signal-transmitting means any quantity stored by said signal-altering means when the operation of said operating means is terminated.

10. The combination of claim 9 and wherein a second light-responsive circuit means is electrically connected with said signal-transmitting means for responding to a range of light intensity at which film in the camera does not have a linear characteristic with respect to the change in light intensity, said second light-responsive means altering the signal in accordance with the film characteristics.

11. The combination of claim 9 and wherein a second light-responsive circuit means is electrically connected

with said signal-altering means for automatically responding to a range of light intensity at which the film in the camera does not have a linear relationship with respect to the light intensity, for altering the quantity stored by said signal-altering means to compensate for the non-linear characteristic of the film at said range of light intensity.

12. The combination of claim 1 and wherein said operating means includes an oscillating circuit means electrically connected with said selecting means for delivering operating pulses thereto, said signal-altering means being electrically connected with said oscillating circuit means to be operated thereby for storing electrical quantities cyclically between said operating pulses and having magnitudes which gradually increase from one pulse to the next, so that when said operating means stops operating at an instant between pulses the stored electrical quantity of said signal-altering means will form an altering signal to be delivered to said signal-transmitting means, light-responsive circuit means forming part of said operating means for determining the operation thereof in accordance with the lighting conditions, and time-limiting circuit means electrically connected with said operating circuit means for limiting the operation thereof to a predetermined time in-

25 terval.

13. The combination of claim 6 and wherein said signal-altering means includes a light-responsive component electrically connected with said capacitor for altering the charge thereof, an adjustable diaphragm co-acting with said light-responsive component for adjusting the amount of light received thereby so as to adjust the extent to which the charge on the capacitor is altered by said light-responsive component, and said signal-altering means including a diaphragm-adjusting means operatively connected with said diaphragm for adjusting the latter to alter said one timing signal.

14. The combination of claim 6 and wherein said signal-altering means includes a transistor electrically connected with said capacitor for altering the charge thereof.

15. The combination of claim 9 and wherein said oscillating circuit means includes a unijunction transistor.

16. The combination of claim 9 and wherein said oscillating circuit means includes a rotary variable resistor and a motor operatively connected thereto for continuously operating the same during said duration of operation determined by said light-responsive circuit means.
